UNITED STATES PATENT OFFICE.

RALPH E. GILMAN, OF PITTSBURGH, PENNSYLVANIA, ASSIGNOR TO WESTINGHOUSE ELECTRIC AND MANUFACTURING COMPANY, A CORPORATION OF PENNSYLVANIA.

TURBO END BELL.

1,272,420.

Specification of Letters Patent. Patented July 16, 1918.

Application filed March 4, 1915. Serial No. 12,132.

To all whom it may concern:

Be it known that I, RALPH E. GILMAN, a citizen of the United States, and a resident of Pittsburgh, in the county of Allegheny and State of Pennsylvania, have invented a new and useful Improvement in Turbo End Bells, of which the following is a specification.

My invention relates to inclosing end members or end bells for dynamo-electric machines, and it has for its object to provide an end bell in which the heating caused by magnetic conditions within the dynamo-electric machine is reduced to a minimum.

15 A further object of my invention is to provide a device that is simple and inexpensive to construct and which may be readily embodied in existing types of end bells and thereby improve the efficiency and operating characteristics of the associated dynamo-electric machines.

In the design and construction of dynamo-electric machines and especially of turbo generators of large capacity it has been 25 found desirable to provide end bells that completely inclose the end portions of the machine, owing to the necessity of having the ventilating system under pressure. The iron or steel end bells that have heretofore 30 been employed have been subject to excessive heating caused by fringing magnetic lines of force from both the field magnet and armature members of the machine that enter the end bells in a direction substantially normal to the faces thereof. The eddy 35 currents produced by the above mentioned fringing magnetic field are particularly noticeable in turbo generators of a well-known type of construction in which the end portions of the armature coils extend beyond the core and into the end bells.

The above-mentioned objections may be overcome by the obvious expedient of moving the end bells far enough away from the field magnet and armature members to limit the number of magnetic lines of force entering them to a reasonable value. The use 45 of such expedient is, however, open to serious objections for the reason that it necessitates a further separation of the shaft bearings, and it is well known that, in the design of high-speed turbo generators, the distance between bearings should be reduced to the smallest possible limit.

55 By my invention, I propose to eliminate

the heating due to the circulation of eddy currents in the end bells, and to provide end bells that may be mounted as closely to the field magnet and armature members as may be desirable, thereby allowing the shaft 60 bearings to be brought as closely together as clearances will permit. In the construction of an end bell in accordance with my invention, that portion of the end bell adjacent to the field magnet and armature 65 members is formed of non-magnetizable and insulating materials for the purpose of eliminating the objectionable eddy-current losses. The complete end bell is preferably formed of two half sections to facilitate its 70 assembly.

In the accompanying drawings, Figure 1 is a view, in front elevation, of a portion of an end bell constructed in accordance with my invention; Fig. 2 is a view, in side 75 elevation, of an end bell mounted on the stator of a dynamo-electric machine; Fig. 3 is a sectional view along the line CD of Fig. 1; Fig. 4 is a sectional view along the line AB of Fig. 1; Fig. 5 is a sectional 80 view along the line EF of Fig. 1, and Figs. 6, 7 and 8 are detail views of parts of the structure shown in Fig. 1.

A dynamo-electric machine comprises a stationary armature member 1 provided 85 with a plurality of windings 2, and a field magnet member 3 rotatably mounted on a shaft 4. A half-section 5 of an end-bell member, preferably formed of cast iron or any other suitable material, is provided with 90 an outwardly projecting flange 6 that is adapted to be secured to the stator frame 1 by means of a plurality of bolts 7 and is disposed between the field-magnet member 3 and the pedestal bearing 8 for the shaft 4. 95 The member 5 is so formed as to inclose one-half of the end portion of the machine and is provided with a plurality of lugs 9 whereby two similar half-sections may be drawn toward each other and secured together to 100 form a complete end bell by means of through-bolts 10. A semi-circular opening 11 is provided in the member 5, and that portion thereof surrounding the opening is provided with a concentric annular groove 105 12. An annular ring 13, preferably formed of brass or other suitable non-magnetizable material and with an inside diameter somewhat larger than that of the shaft 4, is supported concentrically, with respect to the 110

shaft, by means of a plurality of equally spaced and radially extending arms 14 that are secured, at their outer ends, in the groove 12 of the member 5 by means of bolts 15. The arms 14 are formed of brass or other suitable non-magnetizable material and are formed with parallel end portions connected by an inclined middle portion so that the ring 13 is held inwardly toward the rotatable field-magnet member 3, thereby allowing the shaft bearing 8 to be located closely adjacent to the machine. The arms 14 are secured, at their ends, in an annular groove 16 formed in the ring 13, by means of bolts 17. The skeleton frame, thus formed by the arms 14 and ring 13, serves to support a plurality of sections 18 formed preferably of micarta or other hard and durable insulating material and provided, along their edges, 20 with notches 19, as best shown in Fig. 6. The inclined portions of the arms 14 and a plurality of strips 20 of insulating material are provided with corresponding holes 21 so that adjacent sections 18 may be secured between the arms 14 and strips 20 by means 25 of bolts 22. A plurality of insulating washers 23 are inserted between the ring 13 and the arms 14, or at any other suitable point, in order to prevent the existence of a closed 30 electric circuit between the ring 13 and the end bell member.

From the foregoing description, it is apparent that that portion of the complete end bell adjacent to the extending portions of 35 the armature windings 2 and the field magnet member 3 is formed entirely of insulating and non-magnetizable material in order to avoid excessive heating of the end bell produced by the cutting of the magnetic 40 lines of force surrounding the armature and traversing the field magnet and armature core members.

While I have shown my invention in its simple and preferred form, it is not so limited but is susceptible of various modifications within the scope of the appended 45 claims.

I claim as my invention:

1. In a dynamo-electric machine, the com-

bination with a metallic end bell for partially closing one end of said machine, of an annular disk of insulating material extending from said end bell to the shaft of said machine for completely inclosing the end of said machine. 50

2. In a dynamo-electric machine, the combination with a metallic end bell for partially closing one end of said machine, of an annular disk of insulating material extending from said end bell to the shaft of said machine for completely inclosing the end of 60 said machine, said disk comprising a plurality of readily separable segments, and a plurality of radial supports rigidly secured to said end bell for holding said segments in place. 65

3. In a dynamo-electric machine, the combination with a metallic end bell for partially inclosing the ends of said machine, of an annular disk for completely closing the 70 end of said machine, said disk comprising a metallic ring closely encircling the shaft of said machine, a plurality of radial supports secured to said bell and said ring and insulated from said ring, and a plurality of segments of insulating material positioned between said supports and held in place thereby. 75

4. In a dynamo-electric machine, the combination with a metallic end bell for partially inclosing the ends of said machine, of annular disks for completing the closure of the ends of said machine, each of said disks comprising a metallic ring closely surrounding the shaft of said machine, a plurality of 80 radial supports rigidly connected to said bell and said ring and insulated from one of said members, a plurality of notched segments of insulating material, and a plurality of strips adapted to be secured to said supports for holding said segments in place. 85

In testimony whereof, I have hereunto subscribed my name this 24th day of Feb. 1915.

RALPH E. GILMAN.
